UNITED STATES PATENT OFFICE.

EMMETT A. SAUNDERS, OF SOUTH BEND, INDIANA.

PROCESS FOR MAKING RUBBER FOOTWEAR.

No. 927,287.

Specification of Letters Patent.

Patented July 6, 1909.

Application filed February 24, 1905, Serial No. 247,101. Renewed September 8, 1908. Serial No. 333,779.

To all whom it may concern:

Be it known that I, EMMETT A. SAUNDERS, a citizen of the United States, residing in South Bend, Indiana, have invented a certain new and useful Improvement in Processes for Making Rubber Footwear, of which the following is a specification.

This invention has relation to an improved method for manufacturing integral or seamless rubber boots and shoes, whether lined 10 with fabric or unlined.

The principal object of the invention is the production of improved rubber footwear which, by reason of its seamless character, 15 has none of the disadvantages of a permanently cemented article; and wherein the under parts of the shoes on the one hand and the entire uppers on the other hand possess each the peculiar characteristics best adapted 20 to their own necessities under conditions of use.

Seamless rubber footwear has been hitherto manufactured by building up the whole boot or shoe on a last and vulcanizing the 25 parts altogether to produce an integral article of manufacture. In some cases this vulcanization takes place by exposure to "open heat" in a proper oven. In other cases a mold is provided which incloses the 30 entire boot or shoe and wherein it is subjected to simultaneous heat and pressure to accomplish vulcanization.

The present invention aims to overcome certain disadvantages unavoidably incident 35 to both of the above named modes of treatment. These may be stated as follows: The main objection to vulcanizing an entire shoe by open heat in an oven lies in the fact that all green rubber compounds contain 40 more or less moisture and other materials which form expansible gases on being heated. In consequence, when a rubber shoe is vulcanized by open heat these gases open up cells within the rubber walls, giving the 45 whole a more or less spongy texture. The thin parts of the shoe contain less gas-producing fluids than the thicker portions, owing to the greater expressive effect of the forming rollers or calenders on thin sheets than on

50 thicker masses. Hence the sponginess developed during vulcanization is not noticeable in these thinner portions, and such lack of solidity as does exist is rather beneficial than otherwise, as it promotes elasticity and pliability. The thicker portions of the shoe, 55 however, containing as they do a greater

amount of moisture etc., suffer a greater expansion and are converted into rubber sponge covered with a thin outer layer of firmer material. Wear soon penetrates this latter layer and before long a thick sole so made often absorbs and, so to speak, pumps up water into its interstices with every step. The result of this, of course, is a rapid deterioration. The second process above mentioned and hitherto used is also open to objections. Where the entire shoe is placed in a mold for vulcanization under pressure, the sponginess above mentioned is prevented in the thicker parts but the softness is also suppressed in the thinner portions of the shoe. As heretofore mentioned, this softness is beneficial in the thinner walls, and its suppression tends to brittleness in the very parts which must be allowed to yield when the shoe is taken off or put on, and must bend or wrinkle when on the foot. Another important disadvantage met with in this prior process is that the thicker parts, including the heel, the sole and those portions of the remainder of the shoe in direct contact therewith, require more prolonged action than the uppers. It results from this that either the uppers are overcured during a given treatment, or the aforesaid thicker portions are not sufficiently vulcanized. If the uppers are overcured they are hard, inelastic and unyielding and, as the strains of wear on the uppers are pulling and bending strains, quick deterioration is the result. If, on the other hand, the thin uppers are not vulcanized too hard, the thicker parts at sole and heel are left too soft for resisting the wear to which they are subjected. This wear takes the form of shock and abrasion, and a tough, hard, relatively unyielding condition is best in these portions of a boot or shoe.

By the practice of my present invention I am able to produce a shoe having a soft elastic and pliable texture in the thin walls of the upper portions but free from spongy or cellular structure in those thicker portions at the bottom of the shoe which are intended to resist shocks and abrasive action.

In carrying out this process I may make use of any desired apparatus whether novel or well known, and an example of suitable means is illustrated in the accompanying drawings, wherein—

Figure 1 is a cross section of one form of pressing and curing means with a shoe on its

last shown in the operating position and Fig. 2 is a perspective view of a rubber sole ready for application to a shoe in the mold shown in Fig. 1.

5 In practicing my improved process I preferably proceed as follows: The body of the shoe including the inner sole all shown at 1 in Fig. 1, is built up in the usual manner on a last 2, being constructed of properly shaped 10 parts temporarily cemented together. The thick outer rubber sole 3 is separately prepared, being either formed green or partly vulcanized in a press in a well known manner. The sole shown in Fig. 2 is a typical 15 example of this part as prepared for application to the shoe. It is concave in transverse section to fit the convexity of the shoe body, and is preferably provided with an upturned edge 4, which is adapted to fit closely 20 all around the lower edge of the shoe body. The form of sole illustrated is not essential to my invention the scope of which covers the use and application of a mere tap sole or of a heel alone. The shoe body and the 25 thick lower part to be applied thereto having been thus separately prepared, the latter is placed in a mold 5 into which it fits snugly, which mold is combined with means for pressing the shoe body, while still on the last, 30 down onto the sole in said mold. In the illustrative form of apparatus shown in the drawings, this takes the shape of an arch 6 fitted with a screw 7 having a hand wheel 8. The last with the shoe body upon it is placed 35 upon the sole 3 so as to fit within the upturned edge 4 and the screw 7 is turned down hard upon it. The action of the convex body when thus forced down into the concave sole when in the mold 5 is to create a 40 pressure between the soft meeting surfaces at all points, and thus the sole is pressed upon the shoe body, not only on the under surface, but horizontally along the entire length of the upturned edges 4.

45 In order to carry out my process, the mold must be heated to a proper vulcanizing temperature and this may be accomplished in any manner desired. In the apparatus shown in the drawing the mold 5 is hollow as 50 shown and the heat is supplied by steam entering for instance at 9 and returning at 10.

I have found that the last should be made of metal in order to produce the best results, as a wooden core or last is subject to changes 55 in size by weather conditions.

By the means above described there is created a strong continuous pressure which is preserved during the period of vulcanization of the lower shoe body and joined surfaces, or 60 until this process has been carried so far that the material is able of its own resistance to suppress all formation of sponginess under the further influence of heat. When the rubber reaches this last named condition it 65 may be said to be "set", and this word is

used in that sense in my claims. This word is intended to express a sufficient degree of vulcanization to prevent sponginess on application of further heat.

Local vulcanization in a mold as above 70 described must be continued at least to such a point as to "set" the composition in the whole under part of the shoe before the mold is taken off. It may be carried further than this without departing from my invention. 75 The process having been carried to this point, the shoe is taken from the mold and, while still upon the last, is subjected to the proper vulcanizing temperature in an oven without the application of pressure. The 80 sole and heel being set, there is no danger of sponge therein and the manufacturer is free to secure the best results in the uppers without danger to the remainder of the shoe. It is, of course, obvious that removal of the 85 shoe from the mold is not an essential step, as the vulcanizing of the uppers by open heat can be carried out quite as well while the sole is still in the mold. My broader claims are therefore not limited to a process including 90 this step of removal from the mold.

The apparatus whereby my process is carried out forms no part of this invention, as any form of machine appropriate to accomplishment of the steps above described may 95 be employed.

In the following claims the term "sole" is intended to cover either the tap sole or heel or both together and whether extending upward on the side of the shoe body or not. 100

What I claim is—

1. The process of making rubber foot wear which consists in building up the article entire of practically uncured material and vulcanizing the same by subjecting the sole 105 and those parts of the upper which are contiguous thereto to longer heating than the remainder of the article, substantially as described.

2. The process of making rubber foot 110 wear which consists in building up the article entire of practically uncured material, partly vulcanizing the sole and those parts of the upper only which are contiguous thereto under pressure in a mold, and then vulcanizing 115 the entire article at once, substantially as described.

3. The process of making rubber foot wear which consists in building up an article of practically uncured material around a last, joining the sole to the uppers by partly vulcanizing said sole and those parts of the uppers only which are contiguous thereto while under pressure between substantially unyielding surfaces, and lastly completing 120 the vulcanization of the shoe outside of the mold, substantially as described.

4. The process of making rubber foot 125 wear which consists in applying a wholly or partly green sole to the remainder of the 130

article before the latter is set, heating the sole and those parts of the uppers only which are contiguous thereto under pressure until they are set, removing the pressure and subjecting the whole article to a vulcanizing temperature, substantially as described.

5. The process of making rubber foot wear which consists in building up all but the sole in a green state around a proper last, 10 applying thereto a wholly or partly green sole, squeezing the sole and those parts of the uppers only which are contiguous thereto in a mold against the last while applying heat, and, after the parts so acted upon are 15 set, subjecting the whole article outside of the mold to vulcanizing temperature, substantially as described.

6. The process of making rubber foot wear which consists in building up separately 20 a green body portion on a last and a concave sole wholly or partly green, applying said sole to said body portion while the latter is still on the last, squeezing the sole in a mold against the bottom and side edges of said 25 body portion while applying vulcanizing heat, and, after the parts so acted upon are set, subjecting the whole article outside of the mold to vulcanizing temperature, substantially as described.

30 7. The process of making rubber foot wear which consists in building up the body

portion on an unyielding last, joining the sole thereto by partial vulcanization under pressure in a mold, removing the article from the mold and completing vulcanization 35 of the whole outside of the mold, substantially as described.

8. The process of making rubber foot wear which consists in building up an article of practically uncured material around a 40 metal last, partly vulcanizing the sole and those parts of the upper only which are contiguous thereto while under pressure between metal surfaces and lastly completing the vulcanization of the shoe outside of the mold, 45 substantially as described.

9. The process of making rubber foot wear which consists in forming the uppers of practically uncured material built up around a proper support, placing the structure so 50 formed in contact with the practically uncured surface of the sole, partly vulcanizing the sole and those parts of the uppers only which are contiguous thereto under pressure in a mold by themselves, and then vulcanizing 55 the entire article at once, substantially as described.
